Fig 3

FIG. 1 is a rear elevation view of a bicycle reflector showing my new design;

FIG. 2 is an end elevation view thereof; and

FIG. 3 is a front elevation view thereof.

The cross-hatching which indicates a conventional reflective surface is partially shown in FIGS. 1 and 3 for convenience of illustration. It is understood that this cross-hatching is uniformly continuous over the front of the reflector, and on the rear face around the edge and between the spokes. This reflective surface and the spoke pattern contrast in color.

I claim:

The ornamental design for a bicycle reflector, as shown and described herein.
